(57) **CLAIM**

The ornamental design for a canopy for a vehicle, truck, light delivery vehicle or similar vehicle as shown and described.

DESCRIPTION

FIG. 1 is a perspective rear view of an embodiment of a canopy for a vehicle, truck, light delivery vehicle or similar vehicle, showing my new design;

FIG. 2 is an exploded view thereof, shown from the rear;

FIG. 3 a perspective front view thereof;

FIG. 4 is another exploded view thereof, shown from the front;

FIG. 5 is a top view thereof;

FIG. 6 is a bottom view thereof;

FIG. 7 is a side view thereof, the opposite side being a mirror image thereof;

FIG. 8 is a front view thereof;

FIG. 9 is a rear view thereof;

FIG. 10 is a perspective rear view of a second embodiment of a canopy for a vehicle, truck, light delivery vehicle or similar vehicle, showing my new design;

FIG. 11 is an exploded view thereof, shown from the rear;

FIG. 12 a perspective front view thereof;

FIG. 13 is another exploded view thereof, shown from the front;

FIG. 14 is a top view thereof;

FIG. 15 is a bottom view thereof;

FIG. 16 is a side view thereof, the opposite side being a mirror image thereof;

FIG. 17 is a rear view thereof; and,

FIG. 18 is a front view thereof.

The broken lines shown in the drawings illustrate portions of the canopy for a vehicle, truck, light delivery vehicle or similar vehicle that form no part of the claimed design.

1 Claim, 18 Drawing Sheets
